(57) **CLAIM**

The ornamental design for a portable light emitting diode flashlight, as shown.

DESCRIPTION

FIG. 1 is a perspective view of the embodiment of my invention;

FIG. 2 is a front view thereof;

FIG. 3 is a right view thereof;

FIG. 4 is a left view thereof;

FIG. 5a is a top view thereof; and,

FIG. 5b is a bottom view thereof.
